RACK CONSTRUCTION FOR DISHWASHING MACHINES

Gerald B. Fox, Troy, and Lewis E. Glezen, Shaker Heights, Ohio, assignors to The Hobart Manufacturing Company, Troy, Ohio, a corporation of Ohio

Application March 25, 1953, Serial No. 344,562

9 Claims. (Cl. 211—41)

This invention relates to racks for dishwashing machines and more particularly to a rack construction including removable spacer ribs.

It is a principal object of the invention to provide a dishwasher rack adapted to support dishes, cups, glassware and the like in proper position for washing, rinsing and drying in a dishwashing machine in which the ribs for spacing the individual pieces to be washed are readily removable, and replaceable to facilitate cleaning, repair or replacement.

It is another object of the invention to provide such a rack in which the ribs are in the form of closed loops which may readily be replaced with new ribs when the plastic coating on the ribs becomes worn with use and the used ribs discarded or recoated, as desired, without requiring replacement of the entire rack.

It is another object to provide a simple and reliable means for retaining the spacers against accidental movement when in operative position, and for locking and unlocking them in such position.

A further object of the invention is to provide such a rack which may be used with one or more ribs removed for varying the spacing between the ribs as desired.

It is a further object of the invention to provide a rack having a removable bottom so that the bottom as well as the ribs may be coated or uncoated as desired, and a coated bottom may be used with the coated ribs and similarly replaced, such bottom being retained in position by the ribs and easily removable when the ribs are removed.

Other objects and advantages of the invention will be apparent from the following description, the accompanying drawing and the appended claims.

In the drawing—

Fig. 1 is a top plan view partly broken away of a dishwasher rack constructed in accordance with the invention;

Fig. 2 is an enlarged fragmentary view along the line 2—2 of Fig. 1;

Fig. 3 is an enlarged fragmentary view on the line 3—3 of Fig. 1;

Fig. 4 is an enlarged fragmentary view on the line 4—4 of Fig. 1;

Fig. 5 is a perspective view on a reduced scale of one of the removable spacer ribs; and

Fig. 6 is a section on the line 6—6 of Fig. 5.

Referring to the drawing, which illustrates a preferred embodiment of the invention, Fig. 1 shows a generally rectangular rack 10 having an open wire framework including opposite pairs of side walls indicated generally by the numerals 11 and 12 and bottom portions indicated generally by the numeral 13 partially underlying the rack along the lower edges of side walls 11 and defining with side walls 12 a central opening 14. Bottom portions 13 as shown in the drawing include lower and upper rows of bars 13a extending horizontally between side walls 12. A pair of horizontal supporting bars 15 extends between and is secured to the upper row of bars 13a, spaced from and parallel to side walls 12. Bars 15 are

2

connected at their center by horizontal tie bar 16 which serves to brace them and to strengthen the rack. Side walls 11 include vertically extending bars 11a supporting the horizontal bars in the sides 11, and side walls 12 similarly include vertical members 18 supporting the horizontal bars in the sides 12.

The parts of this frame-work are formed of a suitable material such as steel wire which is preferably stainless steel or coated with a non-rusting finish such as chromium, and are welded together throughout in properly spaced relation.

On opposite side walls 12, vertical portions 18 have their tops extending above the sides of the rack to provide guides for stacking racks on top of each other. Opposite side walls 11 include a plurality of opposing pairs of horizontally spaced guide members 20, which may each be conveniently formed from a single length of steel wire turned upon itself in the shape of a long narrow U, welded to side walls 11 with their upper ends approximately flush with the top of the frame and having the underlying portions at their lower ends extending inwardly in the direction of the opposite side at approximately a 45° angle, to form an upright portion 21 defining an elongated guide channel open at its upper end and an underlying portion 22, the bottom of the underlying portions being spaced somewhat above the plane of supporting bars 15. As is shown in the drawing, the guide members on the opposite walls are located in parallel spaced facing relation with their respective underlying portions 22 extending toward each other, defining a plurality of pairs of open slots 25 for removably receiving spacer or separator ribs 30.

These separator ribs are shown in the form of rectangular closed loops of steel wire, either of stainless steel or coated with a rust resistant finish, in the same manner as the frame. For many uses, however, as where for example it is desired to reduce the noise of handling dishes, or where the pieces to be washed are likely to chip against the metal, it may be desired to cover the separator ribs with a comparatively soft plastic vinyl or rubber-like material. A coated rib of this type is shown in Figs. 5 and 6, in which the metal frame 31 is covered with a coating material 32. The material should be one capable of withstanding the substantial amount of heat and the relatively harsh detergents which are customarily used in washing and drying dishes and the like. The material known commercially as "Plastisol," which is essentially a dispersion of polyvinyl chloride in a plasticizer, has given satisfactory results for this purpose. In coating the ribs, good results have been obtained by first dipping the metal ribs in an adhesive base coat 33, and applying the final coating 32 in a second dip.

The length of spacing ribs 30 should be very slightly less than the space between opposite side walls 11, and the width of the slots predetermined with respect to the cross-sectional diameter of the spacing ribs in order that when the ribs are received in corresponding pairs of slots on opposite sides of the frame endwise movement will be prevented by contact with the frame members at each end, and sidewise movement is prevented by the respective guide members.

It is desirable in use that the ribs should be held securely in the guide members, and additional rigidity is obtained by positioning the respective guide members of each pair at a small angle to a line normal to the plane of the bottom of the tray, the respective members on opposite sides 11 being oppositely aligned in this manner, so that each guide member is angled slightly away from the vertical in opposite directions. The loops are thereby slightly twisted or distorted in being fitted into the guide members, and their natural resilience holds them firmly in place, minimizing any tendency of the ends of the loops

and guide members to wear against each other which would exist if they were loosely fitted, and, in the case of the uncoated ribs, reducing noise. Angling the guide members as described has the added advantage that any small cross-sectional dimensional variation between coated and uncoated ribs is compensated for, as are any such variations in the diameter of replacement ribs, the ribs being held resiliently in position by reason of the twist caused by the guide members.

The ribs are supported at the bottom on underlying portions 22 of the guide members. Although the frictional engagement of the ribs in the guide members will ordinarily prevent upward movement, the guide members may readily be locked in place, and the drawing shows locking means in the form of a pin 40 which as appears from Figs. 1 and 4 may be slid between portion 22 of the guide members and the closed end portion of rib 30, as indicated by the dotted lines in Fig. 1. The end of the locking pin is bent over to form a stop 41 for positioning the pin in fitting it in place, where it is held by frictional engagement between the ribs and guide members.

Although the separator ribs may be used in a framework having an integral bottom, when coated ribs are used it will probably ordinarily be preferable that the bottom of the rack also should be coated. Accordingly, an interchangeable removable open bottom 45 is provided which may be of steel wire treated to prevent rust or may be coated with the rubber-like material as described in respect to ribs 30. Bottom 45 may conveniently be formed from a plurality of rectangular closed loops 46 having their ends turned upwardly at 47 and welded in spaced position on bars 48. The loops should be so placed and dimensioned that when the bottom is in position ends 47 will be received between vertical portions 18 of sides 12, and the length between upturned ends 47 should be such that the bottom will be received snugly between the sides. Sidewise movement may additionally be prevented by appropriate locking means, such as rings 49 passed around loops 47 and a portion of the side of the rack as shown in the drawing (Fig. 2).

In assembly or in substituting coated ribs and bottom for the uncoated form, bottom 45 is first inserted. Ribs 30 are then positioned in slots 25, where by reason of the angling of the guides in opposite directions and the resilience of the ribs, the ribs are slightly twisted or distorted so as to be held tightly in place, as described. Locking bar 40 is inserted through the spaces defined by underlying portions 22 of the guide members and the end portions of ribs 30, until end portion 41 abuts against the endmost guide member (Fig. 2), and assembly is completed by placing locking rings 49 in position.

The rack in accordance with the invention offers a number of advantages. As pointed out, the portions of the rack coming in contact with the dishes, glassware, and the like to be washed may be either coated or uncoated, as desired, and substitution of one type for the other is easily made. This is particularly desirable in commercial production in that the same frame may be used with either type ribs and bottom.

From the user's point of view, coated or uncoated ribs and bottom may be used interchangeably. If coated ribs and bottom are used, they may easily be discarded or returned to the factory for recoating when they become worn and a substitute set inserted without necessity for replacing the complete rack, resulting in substantial savings. The rack, furthermore, is unusually adaptable in use in that by removing some of the ribs 30, as desired, the spacing between the ribs can be varied as desired, and with either form of ribs the rack so provided is strong and long-lived in use, and adequately firm for the purpose desired.

What is claimed is:

1. A rack for use in dishwashers and the like comprising an open wire framework defining a bottom and opposite pairs of side walls, a plurality of guide members

located in spaced relation on one opposite pair of side walls, each said guide member extending downwardly from the upper portion of said rack and being formed with two laterally spaced wire guides defining an elongated guide channel, the lower portions of said wire guides being connected and extending inwardly toward the corresponding opposite guides, and removable ribs in the form of closed loops fitting between opposite pairs of said guide channels and forming spacers for the dishes in said rack.

5 2. A rack for use in dishwashers and the like comprising an open wire framework defining a bottom and opposite pairs of side walls, a plurality of guide members located in spaced relation on one opposite pair of side walls, each said guide member extending downwardly from the upper portion of said rack and being formed with two laterally spaced wire guides defining an elongated guide channel, the lower end of each said guide member being in the form of an underlying portion extending inwardly 10 of said rack and removable ribs coated with a plastic rubber-like material fitting between opposite pairs of said guide channels and resting on said underlying portions to form spacers for the dishes in said rack.

15 3. A rack for use in dishwashers and the like comprising an open wire framework defining a bottom and opposite pairs of side walls, a plurality of generally upright elongated guide members located in pairs in spaced relation on one opposite pair of side walls, removable ribs in the form of closed loops fitting between opposite pairs of 20 said guide members and forming spacers for the dishes in said rack, said guide members of each pair being mounted with different inclinations to produce a twist in said ribs in operative position resiliently retaining the same against movement in use.

25 4. A rack for use in dishwashers and the like comprising an open wire framework defining a bottom and opposite pairs of side walls, a plurality of guide members located in spaced relation on one opposite pair of side walls, each said guide member extending downwardly 30 from the upper portion of said rack and being formed with two laterally spaced wire guides defining an elongated guide channel, the lower portion of each said guide member extending inwardly of said rack, removable ribs each receivable between a pair of said guide members in an operative position, and locking means cooperating with said plurality of guide members and with said ribs for securing said ribs in their respective operative positions.

35 5. A rack for use in dishwashers and the like comprising an open wire framework defining a bottom and opposite pairs of side walls, pairs of spaced guide members on the inside of an opposite pair of side walls, said guide members extending to a position above the bottom of said framework and having their lower portions extending inwardly toward the corresponding opposite guide members, removable ribs in the form of closed metal loops receivable between a pair of said guide members on each of said end walls and fitting down upon said lower portions, and means cooperating with said ribs and the lower portions of said guide members for retaining said ribs in 40 operative position between said guide members.

45 6. A rack for use in dishwashers and the like comprising an open wire framework defining a bottom and opposite pair of side walls, pairs of spaced guide members on the inside of an opposite pair of side walls, said guide members extending to a position above the bottom of said framework and having their lower portions extending inwardly toward the opposite guide members, removable ribs in the form of closed metal loops coated with a plastic rubber-like material receivable between a pair of 50 said guide members on each of said end walls and fitting down upon said lower portions, and means cooperating with said ribs and the lower portions of said guide members for retaining said ribs in operative position between said guide members.

55 7. A rack for use in dishwashers and the like comprising an open wire framework defining a bottom and opposite pairs of side walls, a plurality of guide members

ing an open wire framework defining a bottom and opposite pairs of side walls, pairs of spaced guide members on the inside of an opposite pair of side walls forming slots therebetween, said guides extending to a position above the bottom of said framework, removable ribs in the form of closed metal loops with their ends receivable in said slots between a pair of said guide members on each of said end walls, and a locking pin insertable below a portion of said guide members and above the bottom of said loops to lock said ribs in assembled position within said guide members.

8. A rack for use in dishwashers and the like comprising an open wire framework defining opposite pairs of side walls, a plurality of guide members located in spaced relation on one opposite pair of said walls, removable ribs in the form of closed loops fitting between opposite pairs of said guide members and forming spacers for the dishes in said rack, and a removable open bottom normally received in said framework below said ribs and retained therein by said ribs when said ribs are in place. 15 20

9. A rack for use in dishwashers and the like comprising-

ing an open wire framework defining opposite pairs of side walls, a plurality of guide members located in spaced relation on one opposite pair of said walls, removable ribs in the form of closed loops fitting between opposite pairs of said guide members and forming spacers for the dishes in said rack, a removable open wire bottom normally received in said framework below said ribs and retained therein by said ribs when said ribs are in place, and means removably connecting said bottom to said framework for preventing endwise movement thereof.
